CLAIM

The ornamental design for a foldable desk for shopping carts, as shown and described.

DESCRIPTION

FIG. 1 is a front elevational view of the foldable desk for shopping carts showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a perspective view thereof in position of use, the broken line showing of a portion of a shopping cart is for illustrative purposes only and forms no part of the claimed design; and,
FIG. 8 is a front elevational view thereof in the folded position.
